EXAMINER'S ROOM.

UNITED STATES PATENT OFFICE.

EDWIN P. CARPENTER, OF WORCESTER, MASSACHUSETTS.

DESIGN FOR AN ORGAN-CASE.

SPECIFICATION forming part of Design No. 13,344, dated October 24, 1882.

Application filed August 24, 1882. Term of patent 7 years.

To all whom it may concern:

Be it known that I, EDWIN P. CARPENTER, of Worcester, in the county of Worcester and State of Massachusetts, have invented and produced a new and original Design for Organ-Cases; and I declare the following to be a description of my said design sufficiently full, clear, and exact to enable others skilled in the art to which it appertains to make and use the same, reference being had to the accompanying photographs, which form a part of this specification.

My design comprises the form, ornamentation, and arrangement of the several portions of the organ-case in the manner illustrated, Figure 1 being a perspective view, showing the end and front of the case, and Fig. 2 being a front view of the case.

The distinctive features of the design are the front of the case A, composed of the pilasters a and panels b c and breast-piece d, severally formed and ornamented as shown; the extended top D, with side pilasters, e, shelves f, and canopy or top F, composed of ornamental fret with corner devices, g, as illustrated; and the end extensions, K, formed with buttressed pilasters l, relief-columns m, and ledges or shelves p, shaped and decorated substantially as shown.

I contemplate the use of this design in the following modifications, viz: first, the organ-body case without the top and side extensions;

second, the body-case with top extension, D, and without the side extension, K; third, the body-case with the side extensions, K, and 35 without the top extension; and, fourth, the full case with top and side extensions, as shown.

The panels b may be varied as to their pictorial decorations, and said decorations may be incised, gilded, colored, embossed, printed, or 40 otherwise formed on said panels without material change in the nature of my design.

What I claim as of my design, and desire to secure by Letters Patent, is—

1. The design for an organ-case front, A, 45 composed of pilasters a, panels b and c, and breast-piece d, formed and ornamented as set forth.

2. The design for an organ-case, composed of the front A and top D, with panels, pilasters, 50 shelves, and canopy, formed and decorated substantially as illustrated.

3. The design for an organ-case end, composed of pilasters, columns, and shelves, formed and decorated as shown.

4. The design for an organ-case, composed of the front A, top D F, and ends K, of the form shown and described.

Witness my hand this 15th day of August, A. D. 1882.

EDWIN P. CARPENTER.

Witnesses:

CHAS. H. BURLEIGH,
S. R. BARTON.
